[57] CLAIM

The ornamental design for a trailer aligning device, as shown and described.

DESCRIPTION

FIG. 1 is a front elevation view of a trailer aligning device with the rear view being a mirror image thereof;

FIG. 2 is a top plan view of FIG. 1;

FIG. 3 is a bottom view of FIG. 1;

FIG. 4 is a left end elevation view of FIG. 1; and,

FIG. 5 is a right end elevation view of FIG. 1.

For ease of disclosure, a portion of the trailer aligning device has been shown cut away in FIGS. 2-3.
